UNITED STATES PATENT OFFICE.

DAVID B. BAUDER, OF ABRAMS, WISCONSIN.

WEATHER-STRIP FOR WINDOW-SASHES.

SPECIFICATION forming part of Letters Patent No. 619,657, dated February 14, 1899.

Application filed October 13, 1898. Serial No. 693,374. (No model.)

To all whom it may concern:

Be it known that I, DAVID B. BAUDER, a citizen of the United States, residing at Abrams, in the county of Oconto and State of Wisconsin, have invented new and useful Improvements in Weather-Strips for Window-Sashes, of which the following is a specification.

My invention relates to spring-actuated weather-strips for window-sashes; and its object is to provide an improved construction of the same whereby the weather-strip makes a tight joint with the window-frame to prevent the entrance of wind or water and to prevent rattling of the sash.

15 The invention consists, essentially, in the combination, with a window-sash having a vertical groove in the side rail, of a weather-strip located in said groove and projecting beyond the rail, a coiled spring located in 20 said groove and bearing against the inner side of said strip, an angular plate or stirrup formed with a screw-hole and a slot, and the slotted portion of a length greater than the depth of the groove and having the end sharpened and driven into the rail beyond the inner edge of the groove, a headed pin secured to said strip and working in said slot, and the fastening-screw, as hereinafter fully described and claimed.

30 In the accompanying drawings, Figure 1 is a perspective view, partly broken away, showing a window frame and sash constructed in accordance with my invention. Fig. 2 is a detail horizontal section of one of the side rails of the sash, showing the weather-strip and stirrup and coiled spring. Fig. 3 is a detail longitudinal section of the same. Fig. 4 is a perspective view of the stirrup.

In the said drawings the reference-numeral 40 1 designates a window-frame of any ordinary or suitable construction.

The numeral 2 designates a window-sash fitting in said frame, and 3 the side rails, each formed with a vertical groove 4 in the 45 outer side, extending from end to end thereof. Located in said groove is a rectangular strip 5, of wood or other suitable material, against the inner edge of which bears a coiled spring or springs 6, seated in said recesses 7 in said 50 groove.

The numeral 8 designates a stirrup consisting of an angular plate comprising a portion

9, formed with a screw-hole 10, and a portion 12, formed with a slot 13. The slotted portion of the stirrup is longer than the depth of 55 the groove and has its end sharpened, so as to form a cutting edge 14. The numeral 15 designates a headed pin secured to the weather-strip and working in the said slot, and 16 is a screw for fastening the stirrup 60 to the sash-rail. I prefer to use two of these stirrups, one near each end and located on opposite sides of the sash-rail, and in practice the strip is located in the groove in the rail and the slotted portions of the stirrups 65 are driven between the strip and sides of the groove in the rail, and the said slotted portions, being longer than the depth of the groove, will penetrate the rail back of the groove and be thereby held against vertical movement. 70 The screws are then passed through the screw-holes and screwed into the rail. The coiled springs will press the weather-strip against the window-frame, the guide-pins and slots enabling the strip to move in and out. A 75 tight joint will thus be made which will effectually exclude rain, snow, and wind, will prevent rattling of the sash, and will also act as a fastener for holding the sash at any position that it may be raised by the frictional 80 contact of the strip with the window-frame.

Having thus fully described my invention, what I claim is—

The combination with a window-sash, the side rail of which is formed with a vertical 85 groove, of the weather-strip located in said groove, the coiled springs also located in said groove and bearing against said strip, the stirrup comprising the angle-plate, one portion of which is formed with a screw-hole and 90 the other portion with a slot, and said slotted portion being of a length greater than the depth of the groove and having its end sharpened and driven into the said rail back of the groove, the headed pin secured to said strip 95 and the fastening-screw, substantially as described.

In testimony whereof I have hereunto set my hand in presence of two subscribing witnesses.

DAVID B. BAUDER.
